UNITED STATES PATENT OFFICE

EDWARD E. CURTIS, OF LAKEWOOD, OHIO, ASSIGNOR TO THE OSBORN MANUFACTURING COMPANY, OF CLEVELAND, OHIO, A CORPORATION OF OHIO

ROTARY BRUSH

Application filed February 2, 1928. Serial No. 251,325.

This invention relates to brushes and more particularly to rotary brushes, and it is among the objects of the invention to provide a construction which is especially adaptable to high speed operation, and which is not unduly complicated for manufacture. Other objects and advantages will appear as the description proceeds.

To the accomplishment of the foregoing and related ends, the invention, then, consists of the means hereinafter fully described, and particularly pointed out in the claims, the following description and the annexed drawings setting forth in detail but one of the various forms in which the principle of the invention may be employed.

In said annexed drawings:—

Fig. 1 is a side elevation of an embodiment of the invention; Fig. 2 is a section taken as indicated by the line II—II, Fig. 1; and Figs. 3 and 4 are detail sections taken as indicated by the lines III—III and IV—IV, Fig. 1.

The brush tufts 1, preferably set in a twist, are strung on a wire holder 2. In the detail form shown, the ends of the wire holder are brought together and secured as a ring, in any suitable way, for example by welding. Lateral plates are provided and such plates may take the form of side plates 3 and 4, the one provided with outstanding tongues 5 and the other with corresponding openings or slots 6. These plates are assembled with the wire in such a position that the tongues lie just outside of the wire and also enter between groups of the tufts 1, and are secured in final position by clinching down the ends of the tongues projecting through the slots on the far side. With the ends of the tongues thus clinched down, the entire assemblage is secure.

It will thus be seen that the tongues buttress or sustain the thrust of the wire core outwardly, and at the same time serve to hold the tufts in position against travel around the wire holder; and the assembled

plates provide means for applying the brush to a driving arbor. With such a compact construction, thrusts in the particular directions imposed in operation are provided for and the construction as a whole affords a secure and reliable arrangement of brush elements such as to be well adapted for severe usage under high speed operation.

Other modes of applying the principle of the invention may be employed, change being made as regards the details disclosed, provided the means stated by any of the following claims, or the equivalent of such, be employed.

I therefore particularly point out and distinctly claim as my invention:

1. A rotary brush comprising in combination a central ring composed of two mating annuli each having a channel about its inner periphery, a plane annular surface immediately beyond said channel and a second plane annular surface beyond said first-named annular surfaces and offset therefrom a distance equal to the depth of said channels, one of said second-named surfaces having tongues radially disposed in the direction of their width and the other said surface having radial slots corresponding thereto, said tongues being of sufficient length to pass through said slots and be bent over at their ends, said two last-named plane surfaces defining between them a channel peripherally open, a circumferential wire in said channel inward of said tongues, a plurality of radially disposed tufts of bristles seated in said channel, said bristle tufts being bent upon themselves over said wire.

2. A rotary brush comprising in combination a central ring composed of two mating annuli each having a channel about its inner periphery, a plane annular surface immediately beyond said channel and a second plane annular surface beyond said first-named annular surface and offset therefrom a distance equal to the depth of said channel,

one of said second-named surfaces having tongues radially disposed in the direction of their width and the other said surface having radial slots corresponding thereto, said tongues being of sufficient length to pass through said slots and be bent over at their ends, said two last-named plane surfaces defining between them a channel peripherally open, a circumferential wire in said channel inward of said tongues, a plurality of radially disposed tufts of bristles seated in said channel, said bristle tufts being bent upon themselves over said wire and twisted, said tongues laterally supporting said tufts at the base.

Signed by me this 30th day of January, 1928.

EDWARD E. CURTIS.
